US00D907620S

(12) **United States Design Patent** (10) Patent No.: **US D907,620 S**
(45) Date of Patent: ** Jan. 12, 2021

(54) **CASE FOR A SMARTPHONE**(71) Applicant: **OTTER PRODUCTS, LLC**, Fort Collins, CO (US)(72) Inventors: **Jonathan Miksch**, Fort Collins, CO (US); **Nathan Northrup**, Fort Collins, CO (US); **Jonathan B. Rayeski**, Fort Collins, CO (US)(73) Assignee: **Otter Products, LLC**, Fort Collins, CO (US)(**) Term: **15 Years**(21) Appl. No.: **29/664,664**(22) Filed: **Sep. 27, 2018**(51) LOC (13) Cl. **14-03**

Primary Examiner — Carla J Wright**CLAIM**

The ornamental design for a case for a smartphone, as shown and described.

DESCRIPTION

FIG. 1 is a front perspective view of a case for a smartphone; FIG. 2 is a rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines throughout the drawing figures depict portions of the case for smartphone that form no part of the claimed design.

1 Claim, 6 Drawing Sheets(56)
